UNITED STATES PATENT OFFICE.

JOHN STONE BERRY, OF PLAINFIELD, NEW JERSEY.

WINDOW STRUCTURE.

Application filed January 8, 1927. Serial No. 159,868.

This invention relates to window structures of the type in which the sashes may be tilted into a substantially horizontal position within the building for cleaning and other purposes.

Window structures of this general type are shown in United States Letters Patent granted to me, Numbers 1,155,200, 1,158,887, 1,391,237, Sept. 28, 1915, Nov. 2, 1915, Sept. 20, 1921, respectively. These patents show pivot devices mounted at the bottom of the side frames of a window casing and adapted to be employed in connection with the sashes to permit them to be tilted inwardly, and at the same time to be automatically locked and held in the pivot devices when in tilted position, as well as collapsible parting strips adapted to be depressed in suitable grooves in the two sides of the window casing by means actuated by the downward movement of the upper sash. The means for actuating each parting strip is also provided with a cooperative pivot member which engages a cooperating member on the sash to form a pivot-axis for the sash.

This arrangement has not been altogether satisfactory in actual practice for any rebound of the upper sash when quickly drawn in to its lowest position caused the sash to bind on its pivot-axis and because of the nature of the pivot, it was often cut off rendering the device inoperative.

One of the objects of the present invention is to improve the various features of my prior structures and particularly to provide a means for automatically locking the outer or upper sash to the window frame immediately upon its being supported on the pivot-axis at the bottom of the window casing.

The present invention also provides an improved construction of the operating mechanism for automatically collapsing the parting strips between the two sashes actuated by the downward movement of the upper sash, so that the parting strips are out of the way when the upper sash is drawn to the bottom of the window casing to be swung inwardly to permit the outside of the pane to be washed.

The foregoing and other features of my invention will now be described in connection with the accompanying drawings forming part of this specification in which I have represented my window in its preferred form after which I shall point out more partic-

ularly in the claims those features which I believe to be new and of my own invention.

In the drawings,

Figure 1 is a vertical section through a window casing having the present improvements applied thereto.

Figure 2 is an enlarged view in section along the line 2—2 of Figure 1, showing one of the latching devices.

Figure 3 is an external view of the locking device of Figure 2 with the head of the screw cut off to show the construction more clearly.

Figure 4 shows the cooperating latching devices employed at the bottom of the lower sash.

Figure 5 shows the latching device employed for holding the upper sash to its pivot, in enlarged perspective.

Figure 6 is a view, partly in longitudinal section along the line 6—6 of Figure 1, of one of the parting strips of the present invention, together with its actuating mechanism.

Figure 7 is a transverse sectional view of the actuating mechanism along the line 7—7 of Figure 6.

Figure 8 is a transverse sectional view of the parting strip along the line 8—8 of Figure 6.

Figure 9 shows the positions occupied by the two sashes when both of them are tilted inwardly.

Referring to the drawings in which similar reference characters denote similar parts throughout the several views, 10 indicates a window casing which may be of any suitable construction, and having slidably mounted therein a lower sash 11 and an upper sash 12, each suspended by the usual weighted cords which in the present case are connected to the sashes by means of metal strips 72. By this arrangement the points of attachment of the cords may be placed relatively near the bottom of the sashes to permit the sashes to be tilted inwardly. Were the cords attached near the tops of the sashes in the usual manner they would not ordinarily be long enough to permit such tilting before the weights reach the top of the window frame. The outer guide strips or beading 13 for the upper sash may be of the usual wooden or metallic type, since they are not modified in accordance with the present invention.

The guide strips or beading for the inside

of the lower sash are each composed of two sections; a section 14 of ordinary wooden or metallic construction, permanently attached to the window casing, and a section 15 pivoted at its lower end to the window casing by means of a screw 16. The upper end of the section 15 is preferably beveled to engage the correspondingly beveled lower end of the fixed section 14. For the purpose 10 of holding the movable section in its normal position in alignment with the fixed section, there is provided a latch 17 shown most clearly in Figure 2 and in great detail described in my Patent 1,391,237, adapted to 15 be set into the strip 15 and provided with a face plate 19 by which it may be attached to the strip.

In addition to the function as a means for locking the movable sections 15 of the guide 20 strips in place on the window casing, this device also serves as means for latching the lower sash in position upon the sections 15, so as to permit the sash to move with the sections when they are tilted inwardly.

25 When the screw is in locking position as shown in Figure 2, that is, when the beading 15 is in normal position, locked to the window casing, the projection 29 is free to pass between the shoulder 24 and the milled portion 25 of the screw to permit the lower sash to be lifted.

For clamping the bottom of the lower sash to the movable guide strips 15, there is attached to the lower end of each strip a member 30 which may also serve as a bearing plate for the pivot screw 16. The member 30 is provided with an offset portion 31 adapted to form one member of a latch, the cooperating member of which is in the form 40 of a tongue 32 attached to the inner face of the lower sash, as shown most clearly in Figure 4.

The devices thus far described constitute 45 means for holding the movable guide strips 15 in normal position in the window casing, and also provide devices for latching the lower sash to the guide strips when it is desired to tilt the sash inwardly.

50 In order to permit the upper sash to be tilted inwardly, it is necessary to provide an arrangement whereby the parting strips between the sashes may be depressed within the window casing. For this purpose there is placed within a groove in each of the sides 55 of the window casing a metallic channel member 36. A second channel member 37 is fitted within the channel member 36, and a third channel member 38 is fitted within the member 37, producing, as shown most 60 clearly in Figure 8, an arrangement which when collapsed will cause both of the members 37 and 38 to lie within the member 36 to permit the upper sash to be tilted inwardly. The channel members 37 and 38 are 65 connected to each other and to the channel

member 36 by means of links 39, in parallel and connected to the channels by pins 40 and 41, which fit within corresponding bearings 42 and 43 on the channel members 37 and 38, respectively, the channels being 70 slotted to permit the links to extend through the same. The inner end of the link extends through a slot in the bottom of channel member 36 and is pivoted as at 44 to the sides of a housing or bearing member 45 which projects from the bottom of the channel 75 member 36 and is fitted in a suitable recess cut in the window casing. There may be as many links as desired, but in the illustrated embodiment of the invention, three such links have been shown. The portion of the parting strip composed of the channel members 36, 37 and 38 need not extend to the top of the window casing, and as shown most clearly in Figure 1, the upper section 80 46 of the parting strip may be of the customary wooden or metallic construction. A housing 47 incloses the ends of the movable members of the parting strip and also serves as a seat upon which rests the lower end of the upper section 46.

The structure of the links 39 and the method of connecting them to the telescoping members of the parting strip avoids the use of rivets or pins extending through the sides of the members and which might interfere with the movement of the members by catching on the edges of other members. The housings 45 protect the ends of the links 85 that extend beyond the inner channel members 36, and also serve as means by which these members may be fastened to the window casing, as well as to receive the pivot pins for the inner ends of the links.

It is intended that the parting strips shall be extended or collapsed by means actuated by the upper sash when it is drawn to the bottom of the window casing. For this purpose link 39 at the bottom of each parting strip is provided with an extension 90 which, by means of a pin 48, is connected to the inner end of an arm 49 rotatively mounted upon the pivot 50 which carries the link. The pivot pin 50 is mounted in the 95 sides of a housing 51 set in a recess in the window casing. The face plate of this housing is extended downwardly as at 52 to cover the lower end of the groove in the window casing which is not occupied by the parting strip. The housing is provided with an extension 53 which serves as a guide for the lower end of the parting strip similar to the member 47 at the top of the strip.

The arm 49 is provided with teeth adapted 100 to engage the teeth of the ratchet on a block 61 adapted to move vertically within the housing 51. As will be readily understood when the upper sash is drawn to its lowest 105 position this block 61 is pushed to its low-

est position thereby collapsing the parting strip on either side of the sash allowing the upper sash to swing out in the room, pivoted on pivots 64.

5 In the action of my device under normal conditions, the spring 62 is not necessary; it is provided however to keep the parts in normal condition should for any reason the parts be compressed by other than the normal operation of the window.

To provide a means for swinging inwardly the upper sash, I provide a pivot 64 in the window casing on each side and this pivot is engaged by a locking device which is attached to the bottom of the upper sash. On each side of the lower member of the upper sash I provide a member 55 having its lower portion 56 extending against the casing and forming an extended foot 57. Pivoted 10 mounted to the member 55 is a latch 67 with extension handles 68 and spring 79 to maintain the latch in the position shown in Figure 6. The latch is provided on its end away from the handle 68 with an oval opening 69 which is adapted to engage the pin or pivot 64 upon downward movement and by virtue of the shape of the toe 70 the latch will ride upon the pivot 64 until it is embraced by the hole or opening 69, when by 15 the action of the spring 79 it will snap over and embrace the pivot 64 securely locking the upper sash to its casing in position to swing down upon the lower sash as shown in position in Figure 9.

35 The operation of the devices described above is as follows: Whenever it is desired to tilt the sashes inwardly for cleaning or other purposes, the lower sash 11 is drawn to the bottom of the window casing, in which 40 position the clip 32 will engage the co-operating member 31 on each of the guide strips 15, and when the screws 20 are loosened to permit the guide strips to be swung inwardly, the projections 29 at the top of the sash 45 will lie beneath the shoulders 24 on the screws, as shown most clearly in Figure 3, which represents the relative arrangement of the parts at this stage of the operation. The shoulders 28 are in engagement with the tops 50 of extensions 26. The lower sash is thus prevented from moving upon the guide strips 55 15, and all of these parts may be tilted inwardly either to a substantially horizontal position as indicated in Figure 9 or substantially as shown in Figure 1, which is the 60 position in which they may be swung inwardly just enough to be held by the bolts 34 in corresponding holes of the members 33, in case it is desired to provide an opening between the upper and lower sashes to provide 65 for the entrance of air for ventilation.

In order to swing the upper sash inwardly, it is drawn to the bottom of the window casing until the foot 57 of the members 55 contact with the block 61 when it is forced

downward and locked upon the pivot 64, which action operates the parting strip collapsing means 61 through its chain of mechanical movements.

When it is desired to restore the sashes 70 to normal position, the upper sash is swung into its vertical position and then lifted by the handles 68 which will automatically unlock the sash from its pivots and immediately upon the upward movement of the sash 75 the part 55 engages the arm 49 and through its chain of mechanism withdraws the channel members 37 and 38 of the parting strips from the channel member 36 so that they are in position to guide the upper sash as it is 80 raised toward the top of the window casing. The operation of restoring the parting strips to their normal position is entirely automatic. There is thus a positive collapsing 85 and restoring action to the parting strips.

After the upper sash has been restored to normal position, the lower sash is swung into a vertical position, and when the screws 20 are engaged with the plates 72 on the window casing, the shoulders 24 of the screws 90 will be withdrawn from engagement with the projections 29 so that this sash may thereafter be lifted as desired.

I wish it distinctly understood that my 95 window structure herein described and illustrated is in the form in which I desire to construct it and that changes or variations may be made as may be convenient or desirable without departing from the salient features of my invention and I therefore intend the following claims to cover such 100 modifications as naturally fall within the lines of invention.

I claim:—

1. A window structure, comprising a casing, a sash slidably mounted in the casing, parting strips for the sash, each comprising a plurality of telescoping channel elements, members connected to the several channel elements for holding them in parallel relation, means connected to one of the members provided with a ratchet, a vertical movable block adapted to be operatively connected to the before mentioned member through its intercommunicating ratchet, said block adapted to move in the path of the sash and be moved by the sash, a stud projecting from each side of the casing in the path of the sash, means attached to the bottom of the sash and adapted to engage and securely hold the stud to form pivots about which the sash may be swung out of the plane of the casing when the elements of the parting strips are collapsed, said means provided with means for unlocking the sash and restoring the parts to normal position. 115

2. The device of claim 1 with the addition of positive connections between the vertically movable block and the collapsible parting strips whereby the strips are collapsed 120 125 130

upon the window sash reaching its lowest position and expanded to normal position when the sash is raised.

3. A window structure comprising a casing having a pivot, a sash, means attached to the bottom of the sash provided with a latch, said latch adapted to engage and hold the pivot on the casing when the sash is in its lowest position, and means to release the latch from the pivot.

4. The device of claim 3 in which the latch is pivotally mounted and provided with a hole adapted to embrace the stud.

5. The device of claim 1 with the addition of means attached to the bottom of the upper sash to operate the latching means.

6. A window structure comprising a casing having a pivot, a sash, means attached to the bottom of the sash provided with a latch, said latch adapted to engage and hold the pivot on the casing when the sash is in its lowest position, a finger lift to disengage the pivot when raising the window.

In testimony whereof I affix my signature.

JOHN STONE BERRY.
